112,137

DESIGN FOR AN AUXILIARY GUARD FOR AUTOMOBILE BUMPERS

Thomas S. Vosbikian and Peter S. Vosbikian,
Philadelphia, Pa.

Application August 2, 1938, Serial No. 79,045

Term of patent 3½ years

To all whom it may concern:

Be it known that we, Thomas S. Vosbikian, and Peter S. Vosbikian, citizens of the United States, residing at Philadelphia, in the county of Philadelphia, State of Pennsylvania, have invented a new, original, and ornamental Design for Auxiliary Guard for Automobile Bumpers, of which the following is a specification, reference being had to the accompanying drawing, forming part thereof.

Figure 1 is a front elevational view of an auxiliary guard for automobile bumpers, showing our new design.

Figure 2 is a side elevational view.

We claim:

The ornamental design for an auxiliary guard for automobile bumpers, as shown.

THOMAS S. VOSBIKIAN.
PETER S. VOSBIKIAN.
